ADJUSTABLE SUSPENSION DEVICE

Ervin J. Casper, San Francisco, Calif.

Application March 7, 1933, Serial No. 659,930

3 Claims. (Cl. 248—328)

This invention relates to an adjustable suspension device.

The object of the present invention is to generally improve and simplify the construction and operation of suspension devices; to provide a suspension device embodying a chain adapted to be hung from a suitable support and a hanger slidably mounted on the chain and adapted to be secured at any point intermediate the ends thereof, and more specifically stated, to provide a hanger having a tubular shank through which the chain extends and a slot forming spaced shoulders at the lower end of the shank to releasably engage the links of the chain and thereby permit adjustment and securing of the hanger with relation to the chain at any elevation desired.

The adjustable suspension device is shown by way of illustration in the accompanying drawing, in which—

Fig. 1 is a side elevation in section showing a suspension device.

Fig. 2 is an end view showing the rear side of the tubular hanger.

Fig. 3 is a sectional view of the tubular hanger showing the employment of a link chain.

Fig. 4 is a sectional view showing a modified form of the hanger.

Fig. 5 is a front view of the hanger shown in Fig. 4, and

Fig. 6 is a cross section taken on line VI—VI of Fig. 4.

Referring to the drawing in detail, and particularly Figs. 1 and 3, it will be noted that the suspension device comprises in general a chain A and a hanger B carried by the chain and adjustable longitudinally thereon to assume different points of elevation.

Different types of chain may be employed. In Fig. 1 a bead type of chain is shown, and in Fig. 3 a link type of chain. The upper end of the chain may terminate in an eye, such as indicated at 3, and may be hung from a hook as shown, or the upper end of the chain may terminate in a hook and as such may be hung from a picture molding, the top edge of a door, or any other suitable convenient support.

The hanger employed in the preferred form comprises a tubular member generally indicated at B. The upper end is open to permit the chain to be passed freely through the tube and is provided with a lip 3a to slidably engage the chain. The lower end of the hanger is arranged at an angle, as shown at 4, and terminates in a hook 5 to permit devices of different character

to be hung or suspended therefrom. The lower end of the tubular portion of the hanger is notched or slotted on its rear side, as indicated at 6, to form spaced shoulders for the purpose of releasably gripping the individual beads or links forming the chain, thus providing a means for adjusting the hanger longitudinally of the chain and for securing the hanger at any elevation desired.

In actual operation the chain is hung from any suitable support and its free end passes through the tubular shank of the hanger. The slotted lower end of the hanger normally engages with one or the other of the links or beads of the chain and supports the hanger against downward movement. If it is desired to raise or lower the hanger, it is only necessary to grasp the hanger with one hand and to exert a downward pull on the lower free end of the chain with the other hand. A pull in this direction pulls the links or beads of the chain out of the slot and by swinging the free end of the chain in the direction of arrow a, see Fig. 1, the chain is kept clear of the slot and the hanger may thus be adjusted upwardly or downwardly on the chain as desired, and when the desired point of elevation is reached the chain is swung in a direction opposite to arrow a, thus pulling it into the slot where one or another of the links or beads will be engaged. Accidental release of the hanger with relation to the chain is prevented due to the weight of the hanger device or object suspended from the hook 5, and accidental release is further prevented by bending of the chain through means of the arcuate form of the hanger.

The hanger due to simplicity of construction and operation is quickly released for adjustment and just as quickly engaged, and when its use is not required the upper end of the chain may be unhooked with relation to its support and the chain may be wrapped around the hanger thus forming a compact bundle which may be conveniently packed or stored as conditions may demand.

The device may be used for hanging pictures and other objects but it is particularly intended as a support for enema bags, and the like, such as indicated at 7. A modified form of the hanger is shown in Figs. 4, 5 and 6.

In this instance a hook 5a is employed similar to the hook shown in Figs. 1 and 3, but in place of a tubular shank a curved plate 8 is employed. This plate is preferably formed

by stamp and die operations and loops or eyes 9 are pressed out of the metal on the rear side to form a guideway for the chain. A lower loop or eye 10 is also formed and this is slotted 5 as at 11 to engage the links or beads of the chain. The loops or eyes 9 perform the same function as the tubular shank of the hanger B and the slot 11 performs the same function as the slot 6, hence the operation and utility of 10 the device shown in Figs. 4, 5 and 6 are the same.

While certain features of the present invention are more or less specifically described, I wish it understood that various changes may be resorted to within the scope of the appended 15 claims. Similarly, that the materials and finish of the several parts employed may be such as the manufacturer may decide, or varying conditions or uses may demand.

Having thus described my invention, what I 20 claim and desire to secure by Letters Patent is—

1. A suspension device comprising a chain adapted to be hung from a suitable support, 25 a tubular member slidably mounted on the chain, a slotted portion formed in one end of the tube and forming spaced shoulders releasably engageable with the links of the chain to 30 secure the tube at any elevation intermediate the ends of the chain, said tube being bent to form an offset in the chain to retain the chain links against accidental release with relation to the shoulders, and a hook on the

tube from which objects to be supported may be hung.

2. A suspension device comprising a chain adapted to be hung from a suitable support, 5 a tubular member slidably mounted on the chain and having a link-engaging portion disposed at one end of the tube and releasably engageable with the links of the chain to secure the tube at any elevation intermediate the ends of the chain, said tube being bent intermediate 10 its ends to form an offset longitudinally of the chain to retain the chain-engaging member against accidental release with relation to the links of the chain, and a hook on the tube from which objects to be supported may be 15 hung.

3. A suspension device comprising in combination a pendant chain and a rigid hanger 20 adjustably mounted upon the chain, said hanger being substantially arcuate in longitudinal section and comprising a portion at its upper end for slidable engagement with the chain, link-engaging means adjacent the lower portion to releasably engage the links of the chain when moved downwardly, and a load-supporting 25 member at the lower end in offset relation with the link-engaging means, whereby when a load is imposed on said load-supporting member the hanger will be tilted in a direction to flex the chain and force the link-engaging means into 30 firm engagement with a link of the chain for the purpose of supporting the load in various elevations.
